Primary Examiner — Janice Hallmark(74) *Attorney, Agent, or Firm* — Lerner, David,
Littenberg, Krumholz & Mentlik, LLP(57) **CLAIM**

The ornamental design for an axial fan, as shown and described.

DESCRIPTION

FIG. 1 is a front perspective view of an axial fan according to my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear perspective view of thereof.

The broken lines shown in the drawings are for the purpose of illustrating environmental structure and form no part of the claimed design.
